UNITED STATES PATENT OFFICE

2,660,631

SIDE BREAK DISCONNECTING SWITCH

Howard R. Harrison, Philadelphia, Pa., assignor
to General Electric Company, a corporation of
New York

Application August 13, 1951, Serial No. 241,578

10 Claims. (Cl. 200—48)

1

The invention relates to circuit disconnecting switches and the principal object is to provide an improved form of side break rotatable blade disconnecting switch mechanism particularly suitable for separate or gang operation in outdoor high voltage power circuit disconnecting service where severe icing conditions may be encountered.

In such service, it is the usual practice to mount the stationary contacts and the rotatable blade of each disconnecting switch on separate high voltage pin type insulators with the supporting pin of the blade insulator rotatably mounted so as to form an overhung pivot for rotatably supporting the insulator and the rotatable switch blade carried on the remote end thereof. In this way the blade operating mechanism can be connected with the rotatable pin so as to be effectively insulated from the high voltage switch blade. But under severe icing conditions the accumulation of ice on the switch blade as well as on the line conductor connected to the blade may become quite large and cause sagging of the conductor and appreciable blocking of the switch operating parts with resultant chances of misalignment of the blade as well as the insulator axis by the extra operating force required to close or open the switch. Also, where large power currents are involved, such a switch construction ordinarily requires a somewhat exposed flexible braided current conducting connector between the rotatable switch blade and the terminal for the stationary line conductor that is to be connected with the rotatable blade and such flexible connector is subject to deterioration from flexing and also to ice blocking difficulties.

Hence, another object is to reduce such difficulties by providing an improved line connection terminal having an enclosing hub and a series of anti-friction rotating current conducting balls housed in races inside the enclosing hub to cooperate with an improved coaxial conducting spindle provided at the pivot end of the rotatable blade for transferring current between the blade and the relatively stationary line connection terminal as well as supporting the stationary terminal on the same rotatable high voltage insulator as the blade.

With the improved construction of the present invention the ice blocking difficulties are materially reduced by practically totally enclosing the improved current conducting terminal mounting spindle that extends coaxial with the axis of the rotatable pin insulator carrying the switch blade and is electrically and mechanically

2

connected to rotate with the blade. The improved line connection terminal is provided with an enclosing hub for coaxial nesting in spaced apart relation with the conducting mounting spindle and the enclosed series of anti-friction conducting balls having an inclined race on the inside of the hub of the connection terminal and a coaxial race on the conducting mounting spindle insure effective current conduction therebetween almost indefinitely with minimum friction and strain upon rotation of the blade even under severe icing conditions. Another series of anti-friction guiding balls preferably are arranged to be spring pressed against an oppositely inclined race inside the annular hub of the connection terminal pad and a guide pin extension of the conducting spindle so as to maintain coaxial alignment thereof as well as axially bias the hub relative to the conducting spindle and thereby maintain a proper contact pressure between the current conducting balls and the races therefor in each angular position of the blade.

Another object is to provide for both limited longitudinal and transverse self-adjustment of a contact tip at the disconnect end of the rotatable switch blade upon engagement or disengagement with its cooperating stationary contacts so as to insure more effective closing and opening of the switch blade under icing conditions as well as more effective current conducting engagement with the stationary contacts in case of any slight misalignment of the rotatable blade due either to inaccuracies in installation or to flexing or other misalignment stresses produced under heavy ice loadings of the switch blade itself and of the line conductor connected therewith.

In accordance with the present invention this is accomplished by providing a relatively movable contact engaging tip for the blade with a yielding spring pressed ball and socket current conducting connection between the tip and the blade together with a lost motion stop for permitting limited universal self-adjustment therebetween in any direction required to loosen and break up any accumulated ice on the tip in opening and closing the switch. To cooperate with the universally self-adjustable blade tip, a plurality of floating contact fingers are resiliently mounted for limited universal movement inside a stationary side break contact housing so as to engage the opposite sides of the blade tip and produce a limited movement thereof in any direction required to establish effective current conduction between the blade tip and a stationary line conductor connection ter-

terminal that extends inside of the housing in end-wise alignment with the blade tip. In this way both improved ice loosening and breaking action as well as compensation for any misalignment of the blade within a limited range in any direction may be obtained.

Further advantages provided by the improvements of the invention will appear in the following description of the accompanying drawing in which Fig. 1 is a perspective view of 2 poles of a three pole gang operated disconnecting switch of the outdoor, high-voltage insulator mounted type embodying the improvements of the present invention in a preferred form.

Fig. 2 is an enlarged front view, partly in section, of the pivot end of the tubular switch blade having an end clamp specially formed for mounting on the top of the rotatable pin type insulator and provided with the improved coaxial conducting spindle form of rotating ball line terminal mounting of the present invention. Fig. 3 is a top view of the switch elements shown in Fig. 2, partly in section to show the detailed construction of these parts.

Fig. 4 is an enlarged side view, partly in section, of the yielding ball and socket mounted tip at the disconnect end of the switch blade that provides limited relative movement of the tip for loosening and breaking ice as well as effecting self-adjusting current conducting engagement with the resiliently mounted cooperating floating contact fingers carried inside the side break stationary enclosing housing.

Fig. 5 is a top view of the blade tip and its cooperating floating contact finger construction shown in Fig. 4 partly in section to show the details of construction. Fig. 6 is a cross-sectional view on the dashed line 6—6 in Fig. 4 showing the blade tip and its cooperating floating contact fingers in self-aligned spring pressed engagement inside the stationary side break enclosing housing.

As shown in the perspective view of Fig. 1, a three pole gang operated disconnecting switch can readily be made up of duplicate switch units 10 and 11 in the quantities desired, each having a separate channel base 12 with the high voltage pin-type insulator 13 rotatably mounted thereon by means of suitable bearings for the insulator mounting pin 14. The stationary insulators 15 have their mounting pins fixed on channel 12 in spaced apart opposing alignment with the rotatable pins 14. As more clearly shown in the enlarged view of Fig. 2, the switch blade 16 carried on the rotatable insulator 13 preferably is of light weight tubular form although other forms may be used if desired and is provided with an end clamp 17 in the form of a split socket so that the blade 16 may be firmly clamped therein in good electrical conducting relation by means of the clamping studs 18. The blade end clamp 17 is provided with an integral mounting flange 20 that can be removably secured to the end cap 21 of the insulator 13 by means of the mounting studs 22 so as to rotate the blade 16 between its circuit controlling positions upon rotation of the insulator 13 through the agency of a suitable operating linkage 23 which may be actuated manually or motor operated as desired.

In order to conduct current to the rotatable switch blade 16, an improved conducting spindle 24 is provided at the pivot end of blade 16 coaxial with the axis of insulator 13. While the conducting spindle 24 may, if desired, be made integral with the mounting flange 20, preferably it is sepa-

4
rately formed and provided with a suitable mounting flange such that it may be clamped in good current conducting engagement with the flange 20 by means of the mounting studs 22. The spindle 24 is provided with an external coaxial race 25 for seating a series of current conducting balls 26 and also with the guide pin 27 that extends the axis of spindle 24 in alignment with the axis of the rotatable insulator 13.

An improved form of line connection terminal 30 is provided with an enclosing hub 31 for mounting in axial nesting relation with the spindle 24 and has the internal inclined race 32 formed to axially nest with the coaxial race 25 in ball retaining relation with the series of current-conducting balls 26 in order to transfer current between the line connection terminal 30 and the switch blade 16 with a minimum of friction and wear over a long period of service. The hub 31 is also provided with the oppositely inclined race 33 for engaging with another series of guiding balls 35 having pressure exerted thereon by means of the floating collar 36 that is biased axially of the guide pin 27 by the compression spring 37. The spring 37 is compressed by means of the collar 36 and the nuts 39 that are screw-threaded on the end of the guide pin 27. Thus by having one end mounted on spindle 24 and the other end provided with ball bearing connections with hub 31 so as to form a resilient connection therebetween the force exerted by the compression spring 37 on the series of guiding balls 35 biases the enclosing hub of the line connection terminal 30 to move axially relative to the guide pin 27 and thereby maintains the proper current-conducting contact pressure on the series of current-conducting balls 26 in each position of the rotatable switch blade 16. At the same time, the two spaced apart series of balls 26 and 35 serve to maintain the enclosing hub 31 in coaxial alignment with the spindle 24 and thus support the line connection terminal on the same rotatable insulator 13 as the rotatable switch blade 16 with a minimum friction and strain upon rotation of the blade even under severe icing conditions. The enclosing hub 31 is provided with the removable top sealing dome 41 and with the bottom sealing ring 42 so as practically to totally enclose the current-conducting spindle 24 and the current-conducting balls 26 thereby effectively protecting these parts from accumulation of dirt, moisture, or ice in outdoor service. In this way the present invention provides improved conducting paths for the current extending from the relatively stationary line connector terminal 30 through the series of conducting balls 26, the conducting spindle 24, flange 20 and end mounting socket 17 directly to the rotatable switch blade 16, and also insures that such improved conducting paths are maintained effective almost indefinitely under all weather conditions.

Referring now to the enlarged views of Figs. 4, 5, and 6, the disconnect end 50 of the tubular switch blade 16 is flattened and provided with a central bulge or dome 51 for cooperating with a concave seat 52 formed in the relatively movable flat bar blade tip 53 so as to form a ball and socket mounting means for permitting limited movement of the tip 53 relative to the blade 16 in any direction. The concave seat 52 of tip 53 is frictionally held in effective current-conducting relation with the bulge or dome 51 by means of the relatively movable through bolt 54 and the compression spring 55 mounted in cup 56 to permit movement of the blade tip 53 in any

direction relative to the rotatable switch blade 16. As shown in Figs. 4 and 5a stop screw 58 extends loosely through a transversely elongated slot 59 in tip 53 into threaded engagement with the flattened end 56 of the rotatable switch blade 16 so as to limit the relative angular movement of the tip 53 with respect to the blade.

As shown in the sectional view of Fig. 4, the stationary line connection terminal 60 for each disconnecting switch unit is in the form of a flat bar mounted on the end cap 13 of the fixedly mounted high voltage pin-type insulator 15 shown in Fig. 1 by means of the mounting bracket 61 having the mounting studs 62 and mounting bolt 63. One end of the terminal 60 extends inside of the two piece side break housing 64 for enclosing the resiliently mounted pairs of opposing contact fingers 65 and 66 that extend over the end of terminal 60 to engage with the opposite sides of the relatively movable blade tip 53. The opposite halves of the two piece side break housing 64 are held in interlocking relation by the mounting bolt 63 with the outer ends of the compression springs 69 and 70 anchored on suitable bosses formed inside the opposite halves of the two piece enclosing housing and the inner ends seated in recesses formed on the contact fingers 65 and 66. These springs serve to bias the contact fingers into effective current-conducting relation with the opposite sides of both the line connector terminal 60 and the relatively movable blade tip 53, and thereby bias the blade tip to move into substantial endwise alignment with the connection terminal 60 in case of any misalignment of blade 16 that may be due to leading or strains produced under icing conditions.

As more clearly shown in the cross-sectional view of Fig. 6 each half of the two piece enclosing housing 64 is provided with an oppositely inclined tapered lip 11 for guiding the blade tip 53 through the side break opening 72 into circuit-closing engagement with the resiliently opposing mounted pairs of contact fingers 65 and 66 enclosed inside the housing 64. Thus, upon the entrance of the blade tip into the housing, the strong biasing action of the springs 69 and 70 on the opposing pairs of contact fingers 65 and 66 will apply sufficient force on the opposite sides of the blade tip 53 to overcome the frictional holding action of the ball and socket contact pressure spring 55 and effect a relative movement of the blade tip 53 in a direction necessary to correct any misalignment of the blade 16 that may exist. Consequently, the overall result is to tend always to bring the flat bar blade tip 53 into endwise current-conducting relation with the flat bar terminal 60 through the contact fingers 65 and 66 engaging the opposite sides thereof. During such aligning action, the side break housing 64 serves to restrict the lateral floating movement of the resiliently mounted contact fingers in the plane of movement of the blade tip 53 as it enters the housing and hence forces the tip 53 to enter into good conducting relation between the resiliently mounted contact fingers 65 and 66 inside the housing 64. The housing 64 likewise serves to restrict the opposite floating movement of the contact fingers when the switch is opened. Endwise movement of the contact fingers is restricted in a similar way by the end walls of the housing 64 that is removably mounted upon and overhangs the end of the terminal connection bar 60. Since the housing 64, contact fingers 65, 66 and springs 69 form a subassembly with connection bar 60 it may be assembled on mounting bracket 61 with

the sidebreak blade receiving lips 15 on the opposite side, if desired, so as to produce opening and closing movements of the switch in an adjacent quadrant.

Whenever the disconnecting switch blade 16 is opened under icing conditions such that ice accumulates upon the exposed operating parts, the limited angular movement of the tip 53 relative to the blade 16 serves to provide an increased leverage that is effective to loosen and break up any solid ice formations that may tend to block the release of the blade tip from the housing 64 and the resiliently mounted contact fingers 65 and 66 enclosed therein. The reverse limited angular movement of the tip also assists when the switch blade is closed under icing conditions.

While I have, in accordance with the patent statutes, shown and described my invention as applied to a particular system and as embodying various devices diagrammatically indicated, changes and modifications will be obvious to those skilled in the art, and I therefore aim in the appended claims to cover all such changes and modifications as fall within the true spirit and scope of my invention.

What I claim as new and desire to secure by Letters Patent of the United States is:

1. A circuit disconnecting switch having in combination a stationary switch contact provided with a connection terminal for one circuit conductor, a rotatably-mounted switch blade for disengaging the stationary switch contact, a pair of relatively-rotatable conducting members having an axial nesting relation, the inner member having means for mounting the member coaxially on the blade to rotate therewith and the outer member having a connection terminal for the other circuit conductor, a plurality of conducting balls having coaxial races formed on adjacent surfaces of the nesting conducting members in axial nesting ball retaining relation for conducting current therebetween, and resilient means for axially biasing the outer nesting member toward the inner member to maintain current-conducting contact pressure on the balls.

2. A switch having in combination a rotatably-mounted insulator, a switch blade mounted on the insulator and provided with a current-conducting spindle coaxial with the axis of the insulator, a connection terminal having an enclosing hub in axial nesting relation with the spindle, a plurality of conducting balls having cooperating races on the spindle and the hub in axially nesting ball retaining relation for rotatably supporting the hub on the spindle and conducting current between the terminal and the blade and means including a spring interconnecting the spindle and the hub for axially biasing the hub relative to the spindle and thereby maintaining current-conducting contact pressure on the balls.

3. A circuit-disconnecting switch having in combination a high voltage insulator having a rotatably-mounted supporting pin at one end thereof, a switch blade mounted on the other end of the insulator for rotation therewith between circuit-controlling positions, a current-conducting spindle extending from the blade substantially coaxially with the axis of the insulator supporting pin, a line connection terminal pad provided with an enclosing hub in axial nesting relation with the spindle, means including a plurality of conducting balls having cooperating races on the spindle and the hub in

axial nesting ball retaining relation for conducting current between the terminal pad and the blade and means including a compression spring surrounding the spindle and having one end mounted thereon and the other end provided with ball bearing connections with the hub and spindle for maintaining coaxial alignment thereof and for axially biasing the hub relative to the spindle for maintaining current-conducting contact pressure between the balls and the races in each position of the blade.

4. A switch having in combination a rotatable pin type insulator, a tubular switch blade having a conducting end clamp provided with a flange for mounting on the insulator to rotate the blade between circuit-controlling positions and provided with a current-conducting spindle in coaxial alignment with the axis of the insulator, a line connection terminal pad having an enclosing hub in axial nesting relation with the spindle and provided with inner spaced apart oppositely inclined coaxial races, a plurality of conducting balls having a race on the spindle in axially nesting ball retaining relation with one of the inclined races on the hub for conducting current therebetween, and a plurality of balls having ball retaining spring means carried by the spindle to press the balls into engagement with the spindle and the oppositely inclined race on the hub for maintaining axial alignment thereof while axially biasing the hub relative to the spindle to maintain current-conducting contact pressure on the conducting balls in each position of the blade.

5. A circuit-disconnecting switch having in combination a rotatably-mounted high voltage pin type insulator provided with an end cap, a switch blade having a mounting member provided with a flange for mounting on the end cap of the insulator to rotate the blade between a circuit closing and a circuit opening position, a conducting socket mounted on the flange coaxially with the axis of the blade and provided with a coaxial external ball race having a series of conducting balls therein, a guide pin fixed in the socket, a line connection terminal pad having a hub for axial nesting with the guide pin and provided with two oppositely-inclined internal ball races, one of said races being formed for axial nesting in ball retaining relation with the balls in the external race formed on the socket for conducting current between the blade and the pad and the other of said races having a second series of balls for engaging with the guide pin, a floating washer surrounding the guide pin and having spring means carried by the guide pin for axially biasing the washer into engagement with the second series of balls and thereby bias the hub axially relative to the pin for maintaining contact pressure on the first series of balls during the rotation of the blade to and from the circuit-closing position.

6. A switch having in combination a rotatable blade having a relatively-movable tip carried thereby and provided with ball and socket mounting means including a spring for maintaining current-conducting pressure between the ball and socket upon limited movement of the tip relative to the blade in any direction and for frictionally holding the tip in the resulting position relative to the blade, and stationary contact means including opposing contact elements for contacting the opposite sides of the blade tip to effect a limited movement thereof relative to the blade in each direction upon cor-

responding misalignment of the blade with the opposing contact elements.

7. A switch having in combination a rotatably-mounted pin-type insulator, a switch blade mounted on the end of the insulator, a relatively-movable blade tip provided with a ball and socket mounting for limited movement of the tip relative to the blade in any direction and having resilient means for maintaining current-conducting pressure between the ball and socket and for frictionally holding the tip in the resulting position relative to the blade, and a separately-mounted pin-type insulator having stationary contact means mounted on the end thereof including a side break housing having opposing contact elements resiliently mounted therein for contacting opposite sides of the blade tip to effect a limited movement thereof relative to the blade in each direction upon corresponding misalignment of the blade tip with the opposing contact elements.

8. A switch having in combination a rotatably-mounted blade having a flat end, a relatively-movable flat tip mounted on the flat end of the blade and provided with ball and socket mounting means including a spring for maintaining current conducting pressure between the ball and socket upon limited movement of the tip relative to the flat end of the blade in each direction and for frictionally holding the tip in the resulting position relative to the blade, and stationary contact means including a flat conductor having opposing pairs of resiliently-mounted floating contact fingers engaging the opposite sides of the conductor and extending from the end thereof for contacting the opposite sides of the tip to effect a limited movement thereof relative to the blade in each direction to substantially align the flat tip in endwise current-conducting relation with the flat conductor through the floating fingers contacting the opposite side thereof.

9. A switch having in combination a switch blade rotatably mounted at one end, a relatively-movable tip mounted on the other end of the blade and provided with ball and socket mounting means including a spring for maintaining current conducting pressure between the ball and socket upon limited movement of the tip relative to the blade in each direction and for frictionally holding the tip in the resulting position relative to the blade, and stationary contact means including a flat conductor bar having a restricted side open housing overhanging one end thereof and provided with opposing pairs of resiliently-mounted contact fingers for contacting the opposite sides of the flat blade tip to effect a limited movement thereof relative to the blade in a direction to substantially align the flat tip in endwise current-conducting relation with the flat conductor bar through the opposing fingers contacting the opposite sides thereof inside the housing.

10. A switch having in combination a pair of pin-type insulators having mounting pins in spaced-apart substantially-opposing alignment, means for rotatably mounting the mounting pin of one of the insulators, a switch blade mounted on the end of the rotatable insulator and provided with a conducting spindle substantially coaxial with the axis of the insulator, a line connection terminal having a hub mounted on and enclosing the spindle, means including a series of conducting balls having cooperating races on the spindle and the hub for conducting current

from the terminal to the blade while maintaining the hub substantially coaxial with the axis of the spindle and insulator, a relatively-movable flat tip extending from the end of the blade and provided with ball and socket mounting means including a spring for maintaining current conducting pressure between the ball and socket upon limited movement of the tip relative to the blade in each direction and for frictionally holding the tip in the resulting position relative to the blade and a flat terminal bar mounted on the end of the other insulator and provided with opposing resiliently-mounted contact elements for engaging opposite sides of the terminal bar and the blade tip to effect a limited

movement of the tip relative to the blade in each direction upon corresponding misalignment of the flat tip with the flat bar.

HOWARD R. HARRISON.
